UNITED STATES PATENT OFFICE.

SAMUEL P. CROSWELL, 2d, OF MEDFORD, MASSACHUSETTS.

SASH-FASTENING.

SPECIFICATION forming part of Letters Patent No. 356,190, dated January 18, 1887.

Application filed August 28, 1886. Serial No. 212,051. (No model.)

To all whom it may concern:

Be it known that I, SAMUEL P. CROSWELL, 2d, of Medford, in the county of Middlesex and State of Massachusetts, a citizen of the United States, have invented a new and useful Improvement in Automatic Window-Holding Devices, of which the following is a full, clear, and exact description, reference being had to the accompanying drawings, forming a part 10 of this specification, in explaining its nature.

The invention relates especially to mechanism adapted to be used upon or in connection with car and other similar windows for locking or holding them, when elevated or open, in 15 any desired position.

It further relates to the use, in connection with this mechanism, of a lock for locking the window when down or closed.

The invention comprises a jaw having a 20 serrated or roughened cam-surface so pivoted in or to the window-sash as to be movable from one side edge outward against the surface of the window-casing; and it is further adapted to be moved outward automatically by a 25 spring, and to be moved inward to release it from engagement with the window-easing by means of a thumb-piece placed above or in close proximity to the central lifting knob or handle by which the window is raised and 30 lowered.

It further comprises the use, in connection with said holding device or jaw, of a bolt which is adapted to be operated by the said thumb-piece, and the connecting devices and 35 spring which serve to hold the jaw.

In the drawings, Figure 1 is a view in elevation of a window and window-casing, a part 40 of the sash and casing being broken out to show the construction of the locking devices. Fig. 2 is a view in horizontal section through the sash and frame to further illustrate, in plan, the said locking devices. Fig. 3 is a view in elevation of a part of the window sash and casing, a portion of the sash and casing being 45 removed to show the locking mechanism, representing the parts in a different position from that represented in Fig. 1, or in that position which they would assume upon the grasping of the handle and thumb-piece preparatory to 50 raising the window. Fig. 4 is a view of the

same parts represented in Fig. 3, showing the position of the locking devices when the window is raised. Fig. 5 is a view in elevation taken from behind the escutcheon-plate. Fig. 6 is a vertical section upon the dotted line xx 55 of Fig. 5.

A represents the window; A', the window-sash; B, the knob or handle by which the window is raised or lowered in the casing.

C is a jaw, pivoted to the window-sash or to 60 an inclosing-case, c, at c'. It has a surface, c², which, preferably, is provided with cross serrations or teeth or otherwise roughened, and which, preferably, is tangential to the arc of a circle struck from the pivot c'. The end of 65 the jaw has a vertical swinging movement upon the pivot c' outward from the sash, to shut upon or against the casing C' of the window-frame. It is not essential that the surface c² of the jaw be eccentric. It is desirable, however, that the pivot-point c' and length of the jaw be such that when it is moved out the central bearing-point of the jaw shall not extend above the line of the pivot.

The jaw C is moved to bring its face in contact with the surface c² of the window-casing by means of the spring d, operating-rod D, and the arm d' of the jaw C, the end of the rod D being connected with the end of the arm d' in any desired way. I have represented the rod 70 as having a recess, d², which receives the end of the arm d'. The spring d is represented as a coiled spring surrounding the rod D, bearing against a stationary shoulder or washer, d³, and the pin d⁴, which extends through the 75 rod; but I would not be understood as confining myself to the use of this form of spring or to its employment in this especial place.

The operating-rod D extends from the jaw horizontally to a position back of the knob, 90 handle, or escutcheon-plate E, and it is there connected with a lever, e, which is pivoted at e' to said plate E, or to any other suitable support. The lever is in the nature of a bell-crank lever, one end, e², connecting with the 95 rod by means of a slot or recess, e³, arranged in its end, which receives the end of the rod D, the rod having a shoulder at its end which spans the slot or recess and bears against the surface of the lever. The other arm, e⁴, of the 100

lever has a long slot, e^5 , which receives the thumb-piece E' . This thumb-piece has a shank having a square section, e^6 , which enters the slot e^7 in the plate E , and the round section e^8 , which extends into the slot e^5 , and a nut, e^9 , is arranged to screw upon the inner end of the round section e^8 and fasten the thumb-piece to the plate E . It will be seen that by this construction the thumb-piece E' has a vertical movement in relation to the handle or knob B , and that it is so connected with the lever e that it can move or slide thereon as the lever is turned upon the pivot.

There may also be used a bolt, F , for locking the window in its lowest position, and it has the end f , adapted to be moved into the bolt-hole f' in the side or portion C' of the window-casing. It is moved into and out of position by the rod D and spring d , and it is connected with the rod by means of the arm or lug f^2 , which extends into the recess f^3 between the two lugs or projections f^4 , extending upward from the upper surface of the bolt. The bolt is otherwise held or confined in the casing c so as to be properly guided and provided with a straight horizontal movement. In order that the bolt may be moved outward sufficiently far to properly enter the bolt-hole f' when the window is in its lowest position, it is necessary to cut away or remove a section of the casing C' immediately above it, as represented in Fig. 1, in order to permit the jaw C to be moved outward and upward to its fullest extent, or so that it may not strike or come in contact with the casing when the bolt is pushed into place.

I have shown the thumb-piece E' as placed immediately above the handle or knob by which the window is lifted and lowered and as centrally placed with it upon the lower cross-piece of the sash. This I consider to be the best position which these parts should occupy on car-windows or small windows of that character. In large windows it will often be desirable to use two knobs or handles instead of one, and to locate them each about one-third of the width of the sash from each side of the casing. When this construction is employed, the locking mechanism, preferably, is arranged to be used in connection with the right-hand handle or knob. I would further say that the thumb-piece may be arranged below the handle or knob or at either side thereof, as preferred; but I consider that such position is not as desirable or advantageous as the one first named.

In operation the forefinger is placed beneath the handle or knob, the thumb resting upon the thumb-piece E' , the window is then lifted, and the natural muscular effort brings the thumb down upon the thumb-piece, so that it is moved into contact with the upper surface of the handle or knob as the lifting movement begins. The window is then lifted to any desired elevation, the thumb-piece released, and the spring throws the jaw in contact with the side of the window-casing. The surface of the jaw immediately engages the casing and acts as a wedge or link in wedging it against the opposite casing and holding it locked in such position. To release the jaw it is simply necessary to move the thumb-piece in relation to the knob or handle so as to draw the surface of the jaw from contact with the casing of the window.

Of course the jaw and connecting devices may be placed in the window-sash or arranged upon the outer or inner surface thereof, as desired, and there may be arranged on that part of the casing of the window against which the jaw is caused to act a strip of brass or other suitable metal, although for ordinary purposes the hard wood of the casing answers very well.

Having thus fully described my invention, I claim and desire to secure by Letters Patent of the United States—

1. The combination of the jaw C , having a serrated or roughened surface, c^2 , pivoted to the window-sash at c' , and having the arm d' , with the push-rod D , connected at its outer end with the jaw-arm d' , the spring d , the rock-lever e , having the slot e^5 , the plate E , having the knob or handle B and a slot, e^7 , and the thumb-piece E' , having the section e^8 , which extends through the said slot e^7 into the slot e^5 in said lever, substantially as described. 95

2. The combination of the jaw C , having a roughened or serrated surface, c^2 , pivoted at c' , and having the arm d' , the bolt F , having the recess f^3 , the rod D , having a lug, f^2 , which enters the bolt-recess f^3 , and a recess to receive the end of the arm d' , the spring d , the knob or handle B , the thumb-piece E' , and the rock-lever e , connecting it with the end of the rod D , substantially as described. 100
